UNITED STATES PATENT OFFICE.

JOHN J. RANDALL, OF BUTTE, MONTANA.

SPRING-HEEL.

1,160,756.

Specification of Letters Patent. Patented Nov. 16, 1915.

Application filed September 8, 1914. Serial No. 860,690.

To all whom it may concern:

Be it known that I, JOHN J. RANDALL, a citizen of the United States, residing at Butte, in the county of Silverbow and State 5 of Montana, have invented certain new and useful Improvements in Spring-Heels; and I do hereby declare the following to be a full, clear, and exact description of the invention, such as will enable others skilled in 10 the art to which it appertains to make and use the same.

This invention relates to spring heels for boots and shoes, and one of the principal objects of the invention is to provide a spring 15 heel comprising two telescopic members preferably made of sheet metal stamped into form and provided with an interior spring and said heel adapted to be connected to a boot or shoe so that when the wearer 20 steps upon the heel it will yield and absorb the shocks and jars of the shoe coming into contact with the pavement or concrete.

Another object of the invention is to provide a metal shoe heel of two telescopic 25 members containing a spring, said spring being substantially the shape of the inside of the telescopic member, and said spring being connected at one end to one of the members and at the opposite end to the 30 other member so that it will yield when the weight of the wearer of the shoe presses upon the front member of the heel.

The foregoing and other objects may be attained by means of the construction illustrated in the accompanying drawing, in 35 which,

Figure 1 is a longitudinal section through the sole portion of a shoe and showing a heel connected thereto and made in accordance with this invention, and Fig. 2 is a horizontal sectional view taken on the line 2—2 of Fig. 1.

Referring to the drawing, the numeral 1 designates the sole of a boot or shoe and 45 2 is the inner sole thereof, while 3 is the counter of the shoe. Connected to the sole 1 of the boot or shoe by means of suitable countersunk screws or rivets 4 is the upper metal heel section 5, preferably made in the 50 form of an ordinary shoe heel and being

hollow, as shown. The telescopic cushion member 6 of the heel is fitted within the member 5, and has a telescopic movement therein, the two members being fitted together to slide freely but to form a smooth 55 connection between the two members so as not to admit snow or dirt into either section. Connected to the inner wall 5^a of the section 5 is a spring 7, said spring at its upper end being connected by rivets 8 60 along the breast line of the heel and said spring being inclined and secured at 9 by suitable rivets or fastenings to the rear curved heel portion of the tread member 6, as shown more clearly in Fig. 1. When 65 the heel is thus attached to a boot or shoe, the weight of the wearer will bear down upon the telescopic member 6 and the spring 7 will yield sufficiently to absorb the ordinary shock and jars incident to walking. A 70 shoe heel of the character described will not be liable to wear away upon one side owing to the yielding character of the same, and the heel may be readily connected to any shoe or boot, and when worn out may 75 be readily renewed.

Various changes may be made in the details of construction without departing from the spirit and scope of the invention as defined in the claim.

What is claimed is:—

A spring heel comprising an upper sheet metal hollow member having side and end walls, a lower sheet metal hollow tread member having side and end walls, said lower 85 tread member being arranged to telescope in said upper member, and a spring substantially of the shape of the members when viewed in plan, said spring arranged to be placed between said telescoping members 90 and to be attached at the lower end portion of one member and at the diagonally opposite end portion of the other member.

In testimony whereof I affix my signature in presence of two witnesses.

JOHN J. RANDALL.
